Edmund M. Thomas,

By *E. M. Thomas*

Attorney.

UNITED STATES PATENT OFFICE.

EDMUND M. THOMAS, OF MILWAUKEE, WISCONSIN.

EXHAUST ATTACHMENT FOR STEAM-ENGINES.

SPECIFICATION forming part of Letters Patent No. 319,759, dated June 9, 1885.

Application filed August 8, 1884. (No model.)

To all whom it may concern:

Be it known that I, EDMUND M. THOMAS, of Milwaukee, in the county of Milwaukee and State of Wisconsin, have invented certain new and useful Improvements in Exhaust Attachments for Steam-Engines; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

My invention relates particularly to locomotive steam-engines; and it consists, essentially, of two automatic exhaust-valves attached to the under side of the steam-cylinders, near each end of the same, and each connected by an exhaust-pipe with a condensing-coil in the tender-tank, and of two passages connected with the exhaust-port of the cylinder, one discharging into the smoke-stack in the usual way, and the other leading into the condensing-coil in the tender-tank, and a slide-valve controlling and regulating the passage of steam through the said passages.

The objects of my invention are, first, means for accurately controlling the draft through the furnace; second, the saving of fuel; third, to more effectually relieve the piston of retarding pressure in the end of the cylinder open to exhaust, and, fourth, to prevent the disagreeable hissing caused by the opening of the ordinary blow-off cocks.

In the accompanying drawings like letters refer to the same parts in each figure.

Figure 1 represents a longitudinal vertical medial section of a cylinder and steam-chest and of the two exhaust-valves attached to the lower side of the cylinder. Fig. 2 is a like view, on a greatly-enlarged scale, of the two exhaust-valves in the lower side of the cylinder; and Fig. 3 is a horizontal medial section of a portion of the exhaust-passages leading from the upper part of the cylinder, showing the valve by which the passage of steam through the said passages is regulated and controlled.

A represents a locomotive-cylinder of the usual construction, provided with the piston B and the piston-rod R.

C is the ordinary steam-chest, located at the top of the cylinder, and provided with the slide-valve D, controlling the induction and 55 ejection of steam through the passages s s', which lead from the said steam-chest C to opposite ends of the cylinder A.

u is the exhaust-passage, located between the passages s s', and connected with the 60 branching passages or pipes M and H, the first of which terminates under the petticoat E in the smoke-stack, and the second leads back into the condensing-coil F F in the tender-tank. An ordinary slide-valve, N, of 65 sufficient size when in its middle or neutral position to close about one-half of each of the ports o o', opening into pipes M and H, regulates the flow of steam into the smoke-stack or tender-tank. It is provided with the valve- 70 rod T, which is connected with the cab of the locomotive, so as to be readily operated by the engineer, who can partially or entirely close or open either of the ports o o', thus diverting the exhaust-steam, as desired, into 75 the smoke-stack, if greater draft is needed, or into the condensing-coil F, if less draft is required.

To draw off the water which might collect in pipe H by the condensation of the steam 80 before it reaches the coil F, I provide a cock, b, located at the lowest point in said pipe.

G G are automatic exhaust-valves inserted into the lower side of cylinder A, and opening from the same upon opposite sides of the 85 piston B.

I are the valves proper, provided with stems L L, slotted near their upper ends and threaded below to engage with threaded perforations in the valve-heads K K, which close 90 the valve-chambers below when they are open at the top into the cylinder. Just below the seats formed in the valve-cases for said valve-heads K annular grooves are cut into the cases, and into these grooves are inserted rubber or flexible rings a a, perforated to receive and fit closely about the stems L L, thereby preventing the escape of steam from the lower ends of the valves when they are open below, or the heads K K are not closed upon their 95 seats. The valves G G are connected by a small pipe, n, which opens into the same directly against the slotted portions of the valve-stems L L, thus permitting the free egress of 100

steam through said slotted stems into said pipe *n*. From the rear valve *G* a pipe, *m*, leads into pipe *H*, thence into the condensing-coil *F* *F* in the tender. A valve, *c*, located in the 5 pipe *m* near its junction with pipe *H*, prevents backflow into the valves *G* *G*.

Instead of the arrangement just described, I may extend the pipe *m* past each valve *G*, which may be connected therewith by a small 10 offset pipe provided with a valve to prevent backflow. With this arrangement the valve *c* is not necessary.

d d are bell-crank levers, pivoted at their upper ends to ears projecting from the cases 15 of valves *G*, and forked at their lower ends, which embrace the pins *f f*, secured in and projecting from the lower ends of the valve-stems *L L*. A rod or bar, *e*, pivoted at each end to said bell-crank levers *d d*, connects them, 20 so that the valves *I I* are compelled to open and close alternately. (See Figs. 1 and 2.)

My device operates as follows: When the valve *D* and piston *B* are in the position shown in Fig. 1, steam will enter the cylinder from 25 the steam-chest *C* through the passage *s*, and the pressure produced thereby, acting upon the valve *I* in that end of the cylinder, closes the same, and at the same time, acting through the bell-crank levers *d d* and their connecting-rod 30 *e*, opens the valve *I* at the other end of the cylinder, from which the steam escapes not only through the passages *s'* and *u* into the passages or pipes *M* and *H*, but also through the pipe *m* into the pipe *H*, and thence into the condensing-coil *F* *F*. When either valve *I* is 35 opened, the lower valve, *K*, upon the same stem is closed, thus preventing escape of steam from the lower end of the valve-case. When, however, either of the valves *I I* is closed and 40 the valve *K* upon the same stem, of necessity, opened, the ring *a*, fitting snugly about its stem *L*, will prevent leakage or escape of steam from the opposite valve through the connecting-pipe *n*. In this way the heat which is 45 usually discharged into the air and wasted through the blow-off cocks is conducted into the tank which supplies the boiler, and is there utilized for raising the temperature of the water to be converted into steam. By 50 closing the port *o* with valve *N* all the ex-

haust-steam escaping through the exhaust-passage *u* will be conducted off by pipe *H* into the condensing-coil, where it will in like manner be utilized for heating the water in the tank. When great draft is desired through 55 the furnace, the valve *N* is shifted to open the port *o* and close the port *o'*, when the steam will escape through petticoat *E* into the smoke-stack.

Any desired degree of draft may be produced by partially opening and closing the ports *o o'*.

The exhaust-valves *G G* may be applied with good effect to stationary engines as well as to locomotives; but the valve *N*, with its 65 connections, is more particularly applicable to locomotives.

Having thus described my invention, what I claim as new, and desire to secure by Letters Patent, is—

1. The combination, with the cylinder *A* and piston *B*, of the automatic exhaust-valves *G G*, attached to the ends of the cylinder *A*, the bell-crank levers *d d*, and the connecting-rod *e*, whereby the closing of one valve causes 75 the opening of the other, the condensing-coil *F*, and a pipe or pipes connecting said valves *G* with said coil *F*, substantially as and for the purposes set forth.

2. The combination, with the cylinder *A* and piston *B*, of the double-headed valves *I K I K*, the bell-crank levers *d d*, the connecting-rod *e*, and a pipe leading out of the cases of said valves into the water-tank, substantially as 80 and for the purposes set forth.

3. The combination, in a steam-engine, of the cylinder *A*, piston *B*, valves *I I* and *K K*, flexible packing-rings *a a*, mechanism connecting said valves, whereby one is opened when the other is closed, and a pipe leading from the 90 chambers of said valves to a condensing-tank, substantially as and for the purposes set forth.

In testimony that I claim the foregoing as my own I affix my signature in presence of two witnesses.

EDMUND M. THOMAS.
